UNITED STATES PATENT OFFICE.

NATHANIEL WOOD HILL, OF BROOKLYN, NEW YORK.

DESIGN FOR A GAME-BOARD.

51,416.

Specification for Design.

Patented Oct. 23, 1917.

Application filed July 14, 1917. Serial No. 180,669. Term of patent 7 years.

To all whom it may concern:

Be it known that I, NATHANIEL WOOD HILL, a citizen of the United States, residing at No. 125 Stratford road, in the borough of Brooklyn, county of Kings, and State of New York, have invented a new, original, and ornamental Design for Game-Boards, of which the following is a specification, reference being had to the accompanying drawing, forming part thereof.

The figure is a top plan view of a game board showing my new design.

I claim:

The ornamental design for a game board, as shown.

NATHANIEL WOOD HILL.

Witnesses:

A. M. VIKBERG,
EDWIN S. HALL.
